J. L. HILDEBRAND

RAZOR BLADE SHARPENER

Filed April 7, 1926

Inventor:
James L. Hildebrand
by Geo. N. Goddard, Atty.

Patented Jan. 3, 1928.

UNITED STATES PATENT OFFICE.

JAMES L. HILDEBRAND, OF LYNN, MASSACHUSETTS.

RAZOR-BLADE SHARPENER.

Application filed April 7, 1926. Serial No. 100,318.

This invention relates to razor blade sharpeners of portable type, and is intended for use in stropping or sharpening either single edge or double edge safety razor blades. Among the objects of the invention is the provision of a device of portable type that shall be very simple in construction, inexpensive to manufacture and highly efficient and rapid in its sharpening action.

Heretofore devices of this type have been characterized by an outer casing or framework adapted to be grasped in one hand and provided with an actuating crank to be turned by the other hand to rotate stropping rollers. I have found that, by providing a manually operated device that can be driven at much higher speed than can the crank-driven devices referred to, a very superior cutting edge can be produced on the razor in a very short interval of time.

In its general features the invention comprises a central fixed supporting post which is constructed to support and accurately position the razor blade to be stropped in accurately fixed position, said post forming the support for an oscillatory frame in which are mounted rotatable stropping rollers, the said post also rotatably supporting a roller-driving sprocket sleeve over which is passed a manually actuated chain, all arranged so as to permit a high speed rotation of the stropping rollers alternately against opposite sides of the edge of the inserted blade.

This and other features of the invention will be described in the following specification and will be defined in the claims hereto annexed.

In the accompanying drawings:

Figure 1 is a plan view showing a complete assembled view of the razor stropper as it would appear when attached to the edge of a door or other support, such as the back of a chair;

Figure 2 is a side elevation of the mechanism shown in Figure 1.

Figure 3 is a central vertical section through the central supporting post which forms the backbone of the structure.

Figure 4 is a cross sectional view through the razor blade holder and rollers on the dotted line plane 4-4 of Figure 1.

Figure 5 is a front end elevation.

Figure 6 is a plan view showing a doubled edge blade and its carrier-plate in interlocked relation.

Figure 7 is a reverse or underside view of the same carrier-plate with a single edge blade mounted thereon.

Figure 8 is a cross sectional view through the blade-carrying plate with a single edge blade attached thereto.

Figure 9 is a front elevation of the attaching plate of the supporting clamp.

In the practice of this invention, according to the form illustrated, I provide a central supporting post 1, of flattened cross section, as shown in Figure 4, which is provided at its inner or anchoring end with an enlargement or head 1^a, and with a reduced projecting stud 2, of cylindrical form, which terminates in a reduced tang or tenon 2^a adapted to be inserted through a supporting plate 20, to which it is clamped by a clamping nut 2^b so as to hold the post 70 rigidly in position to support other parts of the device.

In the preferred form the forward end of this post is provided with an enlargement or spindle head 1^b which is rabbeted, as shown at 1^c, to form a cylindrical bearing for the oscillatory roller-carrying frame, presently to be described.

This supporting post 1 is slotted longitudinally from its outer end inward to form a holding chuck comprising upper and lower jaws between which is pushed in endwise a blade-carrying member 3.

This blade-carrying member 3 comprises, essentially, an elongated flat bar or plate 90 having, along the medial line of one face, a plurality of short projecting studs or pins 3^b adapted to register with corresponding openings in a well-known type of razor blade, and also has a boss or spline 3^a, adapted to enter a channel or groove in the slot of the holding chuck 1, when the blade-carrier and its interlocked blade is inserted and pushed in to stropping position, this manipulation being facilitated by a knob or handle 3^d on the front end of the blade-carrier.

As the device is intended to be used for either double edge blades or single edge blades there is provided, on the reverse side 105 of the plate 3 from the studs 3^b, an oblong shallow pocket or socket for the reception of the thickened or reinforced back portion of the commonly used single blade. The studs 3^b as well as the boss 3^a project sufficiently beyond the upper face of the razor blade, when the razor blade is placed into 110

interlocked relation with the carrier, so that all these members form together an interrupted spline guiding in the longitudinal keyway or groove 1^c, formed in the slot 1^c, thereby preventing lateral displacement of the blade-carrier and blade.

To prevent too easy withdrawal of the blade-carrier in the blade from its holding chuck, a headed plunger or detent 4 projects through the lower jaw to form a frictional contact with the underside of the blade-carrier against which it is presesd by the flat spring 4^a.

The stropping rollers 10 are mounted in an oscillatory frame comprising the inner cross-head or member 5 and a U-shaped yoke 6 rigidly secured thereto thus forming a rigid quadrilateral frame. The outer cross-connecting member 6^a of the oscillatory frame is formed with a middle bearing aperture to receive the annular bearing 1^c, formed on the outer end of the post 1. It will be observed that the bearing aperture in the cross member 6^a of the oscillatory frame is of sufficiently large diameter to allow the passage of the inner head 1^a of said post so that the device may be easily assembled. The post is inserted with its stud end 2, foremost first through the cross member 6^a and then through the cross-head 5^a, the latter having bearing engagement with the cylindrical stud 2 at the inner end of the post. Both cylindrical bearings 1^c and 2 of the fixed central post or arbor, which forms the central support or backbone of the working elements of the device, are provided with flat annular shoulders transverse to the central axis. The cross head 5^a is preferably provided with a peripheral flange to form a protective easing around the train of pinions by which the rollers are rotated.

A distinctive feature of the present improvement consists in the sprocket sleeve 11, provided with an intermediate sprocket member or wheel 11^a, and provided also at its outer end with a pinion 12, preferably of substantially larger diameter than the diameter of the sprocket 11^a. A manually operated sprocket chain 13 passes around the sprocket 11^a and is prevented from slipping off the sprocket by an arcuate guard member 13^a secured to the supporting plate 20 to prevent the chain from accidentally running off the sprocket wheel.

The rollers 10 are journaled in the two cross members 5 and 6^a of the oscillatory frame, and have secured to the inner ends of their journals driving pinions 14, which are preferably considerably smaller in diameter than the driving pinion 12 with which they intermesh. There is a very decided advantage in imparting a relatively high speed of rotation to the rollers when in stropping contact with the blade edges, and this is accomplished first by the use of

a driving chain which has two advantages over a crank drive, namely, that it is possible to attain a much higher driving speed with the chain grasped in the two hands and pulled alternately in opposite directions, and second because the attempt to rotate a small crank at high speed results in the jerky and sometimes reverse movement of the crank, while the chain gives a steady driving pull without this jerky and sometimes reverse movement of the crank. This steady pull is particularly important where, as in the present case, the oscillatory frame carrying the rotary rollers is swung to establish stropping contact between the rollers and the edges of the blade by the friction exerted by the rapidly rotating driving sleeve or pinion against the adjacent cross member 5 of the roller-carrying frame, as it will be seen that a jerky or halting rotation of this pinion will result in an irregular and jerky contact of the stropping rollers with the blade.

The stropping rollers themselves are preferably made by winding strips 10^a, of suitable leather, helically around the rollers to prevent minute nicks in the blade by fine particles of steel removed in the stropping operation. The outer or stropping surface of these strips may be slightly scored transversely to leave suitable shallow score marks or grooves, in this case shown to be of V shape or herring-bone pattern. Such scoring increases the efficiency of the rollers particularly when driven at high speed as it presents a rapid succession of stropping edges, while providing shallow recesses for the reception of the particles removed from the steel blade.

As both hands are needed for the efficient operation of the driving chain particular attention is paid to the means for attaching the supporting post to any convenient object adapted to form a support and to this end the plate 20 is made with three triangularly disposed apertures, to wit, two plain ones 20^b, while the third one is in the form of a keyhole slot 20^c adapted to drop down behind the head of an attaching screw 21^a secured in proper position on a supporting clamp 21 which is also provided with projecting pintles 21^b, adapted to pass through the holes 20^b, the U shaped clamp itself being provided with an anvil 21^b opposed to a clamping screw 21^a.

The supporting clamp 21 is preferably made detachable from the face plate 20, for convenience in packing the device.

From the foregoing description it will be seen that the device is very simple and cheap in its construction since the central supporting post, which carries the strop, is made in one piece and forms an entirely adequate bearing for both the driving sleeve and the oscillatory roller frame, and also

provides a simple and effective chuck for accurately positioning and firmly retaining either a double edge blade or a single edge blade for sharpening. Its supporting clamp 5 allows it to be attached to the edge of a door, back of a chair or to the overhang of a table since the clamping connection, with the plate 20, allows it to be set to any desired angle in relation to its clamping member. 10 The long, steady pull in one direction serves to frictionally hold the rollers in proper continuous stropping contact with the blade edge until the movement of the chain is reversed, while affording a very high speed action of the stropping rollers against the blade. While the chain is being pulled in one direction each roller is operating on its side of the two edges of the blade, and when the pull is reversed it operates on the opposite side of the edge that has just been stropped by the other roller.

It will be seen that the central post forms a fixed arbor that affords support for all the working parts in a most accessible manner. The alternate pulling to and fro of the driving chain, which is kept from leaving the sprocket by the guard or keeper 13^a, permits the rapid rotation of the pinion sleeve 11, which is confined between the adjacent cross or end member 5 of the oscillatory frame and the supporting standard 20, so that the end thrust of this pinion sprocket sleeve is sustained by the member 5 of the oscillatory frame which is held against outward movement by the annular shoulder at the outer end of the cylindrical bearing 2. This affords a frictional contact sufficient to cause the oscillatory roller-carrying frame to be swung in a counter-clockwise direction 40 (having reference to Figure 4) when the driving pinion is rotated in that direction by a pull downward on the left hand end of the chain until the two stropping rolls come in contact with opposite edges of the blade 45 and on opposite sides thereof. At the end of the stroke the chain pull is reversed, the pivotal frame swings through an arc of approximately 90 degrees so that each roller engages the opposite edge of the blade, the rotation of each roller in each instance being from the middle portion of the blade toward its edge since reverse rotation would tend to cut the strop covering of the roller.

A slight pinching action upon the inner end member of the oscillatory roller frame, between the rapidly rotating sprocket sleeve and the confining shoulder of the central post or arbor, is quite sufficient to induce this limited swinging movement of the frame and also to cause a substantial pressure of the rollers against the edges of the blade being sharpened. The sprocket chain forms a positive driving element, free from any frictional slip that might be induced by 60 the frictional resistance to rotation of the

rollers by reason of their pressure against the razor blade.

As a consequence of the above-described construction and arrangement a high speed of rotation for the rollers, in conjunction with a substantial pressure of the rollers against the blade is obtained, as well as a continuous, steady movement, free from slip or jerk and, therefore, a highly efficient sharpening action is produced.

What I claim is:

1. A razor blade sharpener embracing in combination a central fixed supporting post one end of which is constructed to be secured to a suitable stationary support, said post being slotted from its other end to form a pair of gripping jaws, a blade-carrying plate formed to have interlocking engagement with a razor blade placed against its side and to coact with one of said jaws to engage said blade on opposite sides and to hold it in fixed position to be stropped, an oscillatory frame pivotally mounted on said post, rotatable stropping rollers mounted in said frame to have alternating stropping contact with opposite sides of the same edge of the blade, and a chain-actuated gearing train for oscillating said frame and rotating said rollers to sharpen the blade.

2. A razor blade sharpener embracing in combination a fixed supporting post provided at one end with means for attaching it to a fixed support, said post being slotted from its other end to receive and support a blade-carrying member, an oscillatory frame having pivotal bearing engagement with said post, rotatable stropping rollers mounted in said frame and movable with the frame to alternately form stropping contact with opposite sides of one edge of the blade, a sprocket sleeve mounted on the attached end of the post, a pinion secured to said sleeve and having frictional contact with said oscillatory frame, said pinion also intermeshing with pinions on the adjacent ends of the rollers and a driving chain arranged to travel to and fro over said sprocket as it is manually actuated to and fro.

3. A razor blade sharpener embracing in its construction a standard, a central blade-holding post secured at its inner end to the standard, said end being reduced to form a cylindrical bearing between an annular thrust shoulder and the standard, a reversible rotary driving pinion mounted on said bearing, an oscillatory roller-carrying frame having pivotal support on said bearing between the rotary pinion and the thrust shoulder, and being frictionally oscillated by said pinion to be shifted to and maintained in operative position as the pinion rotates to and fro, and rotatable stropping rollers mounted in parallelism in said oscillatory frame on opposite sides of said post, and having driven connection with said pinion.

4. A razor blade sharpener embracing in combination a fixed post provided at one end with means for attaching it to a supporting object, and slotted lengthwise to form a blade-supporting and positioning chuck, a roller-supporting member pivotally mounted on said post, spaced stropping rollers rotatably carried by said member, a rotatable sprocket member supported by said post and 10 having gearing connection with said rollers, and a pull-chain having positive driving engagement with said sprocket to rotate said sprocket member alternately in opposite directions, said roller-carrying member being 15 swung to and fro by friction transmitted from the reversible sprocket member.
5. A razor blade sharpener embracing in combination a fixed post, said post being slotted lengthwise to form blade-supporting 20 and positioning jaws and being provided with an external bearing at each end, an oscillatory quadrilateral frame mounted on said bearings, rotatable stropping rolls mounted in said frame, a reversible rotatable chain-actuated driving member operatively connected with said rollers to rotate them alternately in opposite directions as the chain is drawn to and fro, said frame being 25 swung to and fro by frictional connection 30 with said driving member to present and retain each roller alternately in rotating contact with an edge of the blade until the chain movement is reversed.
6. A razor sharpener embracing in its construction a fixed central blade-holding post provided with bearings at its ends, an oscillatory frame mounted on said bearings, rotatable stropping rollers mounted in said frame on opposite sides of the central post, 35 a driving sprocket sleeve rotatably mounted on one of said end bearings and having a 40 driving gear connection with said rollers to rotate them, a manually operated chain having driving engagement with said sprocket-sleeve to rotate it rapidly to and fro, said driving sleeve having frictional engagement with said oscillatory roller frame to shift it to and fro as the chain movement is reversed, and a guard member extending around the sprocket and the sprocket-engaging portion of the chain to prevent the chain from becoming disengaged from the pinion.
7. In a razor blade sharpener, the combination with a fixed central post, an oscillatory roller-carrying frame pivotally mounted thereon, a chain driven sprocket-sleeve mounted on one end of said post to have frictional engagement with said oscillatory roller frame, a guard member partly surrounding said sprocket to prevent accidental disengagement of the chain, said sprocket-sleeve being provided with a pinion intermeshing with roller driving pinions to cause the rollers to rotate in opposite directions as the position of the frame and 65 the movement of the driving chain is reversed.
8. In a razor sharpener, the combination with a fixed central blade-supporting post provided with means for releasably locking a razor blade in stropping position therein, an oscillatory roller-carrying frame pivotally mounted on said post, a reversible rotary sprocket sleeve also mounted on said post in frictional contact with said oscillatory 70 frame, said sleeve having a pinion forming a driving connection with the rollers carried by said frame, and means for reversibly rotating said sleeve.

In witness whereof, I have subscribed the above specification.

JAMES L. HILDEBRAND.
